UNITED STATES PATENT OFFICE.

PAUL ONNERTZ, OF BERLIN-WILMERSDORF, GERMANY, ASSIGNOR TO ACTIEN GESELLSCHAFT FÜR ANILIN FABRIKATION, OF BERLIN, GERMANY.

PROCESS FOR DYEING FURS, SKINS, HAIRS, FEATHERS, OR THE LIKE.

No Drawing.

Application filed May 15, 1922. Serial No. 561,011.

To all whom it may concern:

Be it known that I, PAUL ONNERTZ, a citizen of the German Republic, residing at Berlin-Wilmersdorf, Germany (my post-office address being Dusseldorferstr. 72, Berlin-Wilmersdorf, Germany), have invented certain new and useful Improvements in Processes for Dyeing Furs, Skins, Hairs, Feathers, or the like, of which the following is a specification.

It is known to dye furs, feathers, hairs or the like with aid of 4-amino-1-oxybenzene. By my present invention tints which differ considerably from those obtained with 4-amino-1-oxybenzene may be obtained by application of derivatives of 4-amino-1-oxybenzene, containing negative substituents such as halogen-, nitro-group in presence of an oxidizing agent, the shades being of an excellent fastness.

The said derivatives are superior to 4-amino-1-oxybenzene because they may be used mixed with other compounds for example with meta-diamine, whereby dyeings are obtained showing the mixed shades of the components, whereas the unsubstituted 4-amino-1-oxybenzene reacts with many other compounds so that the shades thus obtained differ from those of the components.

The following example illustrates my invention, without limiting it:—

The well-washed skin is handled for some hours at ordinary temperature in a bath which contains per litre 2 grams of 2-chloro-

amino-1-oxybenzene, 4 grams of ammonia (of 25% strength) and 30 cc. of hydrogen peroxide (of about 3% strength). The skin is then well-washed and finished as usual, a brownish shade being obtained.

40 The tints obtained on skins prepared with chromium or copper mordants are brown, those on skins prepared with iron mordants are reddish brown.

2,3-dichlor-4-amino-1-oxybenzene dyes 45 gray tints inclining to green; 2-nitro-4-amino-1-oxybenzene, when dyed on furs prepared with chromium- or copper-mordants, dyes brown shades with a reddish 50 tinge.

Having now particularly described my said invention and the manner in which it may be performed what I claim is—

1. Process of dyeing furs, skins, hairs, feathers and the like, comprising treating the same in the presence of an oxidizing agent with a solution of a 4-amino-1-oxybenzene containing a negative substituent.

55 2. Process of dyeing furs, skins, hairs, feathers and the like, comprising treating the same in the presence of an oxidizing agent with a solution of 2-nitro-4-amino-1-oxybenzene.

60 In testimony whereof I affix my signature in presence of two witnesses.

DR. PAUL ONNERTZ.
